UNITED STATES PATENT OFFICE.

JOSEPH R. GREEN, OF WAKEFIELD, MASSACHUSETTS, ASSIGNOR TO THE PHONOHARP COMPANY, OF EAST BOSTON, MASSACHUSETTS, A CORPORATION OF MAINE.

HITCH-PIN FOR STRINGED INSTRUMENTS.

No. 870,283.

Specification of Letters Patent.

Patented Nov. 5, 1907.

Application filed January 28, 1907. Serial No. 354,384.

To all whom it may concern:

Be it known that I, JOSEPH R. GREEN, of Wakefield, in the county of Middlesex and State of Massachusetts, have invented certain new and useful Improvements 5 in Hitch-Pins for Stringed Instruments, of which the following is a specification.

This invention has relation to musical instruments and more particularly to pins for employment in stringed instruments for the attachment of the ends 10 of the strings.

The object of the invention is to provide an improved hitch pin construction by means of which the strings may be held securely without danger of the pin becoming dislocated or yielding under the strain of 15 the string, and yet which will permit the easy insertion or removal of the pin when desired.

On the drawing.—Figure 1 represents a portion of the zither equipped with my invention. Fig. 2 represents a section on the line 2—2 which is very much 20 enlarged to show how the pins are anchored in position by the engagement of their roughened or screw-threaded portions with the walls of the apertures in which they are inserted.

While the invention is applicable to a variety of 25 instruments, nevertheless it is best adapted for such instruments as the zither, harp and the like, of which an example is shown upon the drawing.

Referring to the said drawing, *a* indicates the sounding board, across which are strung strings *b*. I have not 30 illustrated any particular means for hitching the ends of these strings, any suitable means being utilized for this purpose.

At *c* there is a bridge which is on a line intermediate of the ends of the instrument. This bridge is secured 35 to the sounding board *a* and to an interior cross-piece *d*. The bridge *c* is illustrated as notched at *c'* for the passage of the melody strings *b* which are arranged in a chromatic scale.

e indicates what may be termed chord strings. These 40 strings extend from the bridge *c* to the left end of the instrument (not shown) where they are secured by any suitable means. Said strings *e* are stretched over a metallic bar *f* which is supported upon the top of the bridge and their ends are secured to hitch pins *g*, to 45 be described.

The description thus far (except of the hitch pins) relates to the particular form of instrument which I have selected at illustrating the character of one for which my invention is applicable, and I desire to here

have it understood that the invention is not limited 50 to this particular form of instrument but is capable of embodiment in pianos and various other forms of stringed instruments in which a bridge or analogous cross-piece is located above the plane of the sounding board. 55

It will be seen that the sounding board *a* and the lower cross-piece *d* have a plurality of holes or apertures *h* which are slightly inclined with respect to a line perpendicular to the plane surface of the sounding board. These apertures are bored close to the edge 60 or side of the bridge *c* so that the lower edge of the bridge is substantially tangential to the mouths of the apertures.

The hitch pins *g* are preferably formed of wire and each has a shank *g'* which is threaded, corrugated or 65 roughened as at *g''*. The upper end of the pin is bent to form a hook *g³*, which projects laterally from the bridge *c*. The pins *g* are a little smaller in diameter than the holes *h* so that they may be dropped loosely into place and extracted when desired with ease. 70

Fig. 2 represents the construction greatly magnified, and it will be seen from this figure that, when the pin is inserted in the aperture and the string *e* is drawn taut by the tuning pin to which it is connected, the pin *g* will be tilted about the edge of the bridge as a fulcrum, so that the threads *g²* will be caused to embed 75 themselves in the wall of the aperture whereby the pin will be securely held against outward movement.

The difference in size of the pin and its aperture may be exaggerated somewhat in the figure, and the 80 inclination of the pin and the aperture relatively to the perpendicular to the plane of the sounding board may be at a little greater angle than is necessary, but I have practically demonstrated it to be a fact that, by constructing the pin with a hook and locating it in 85 a slightly enlarged aperture, so that it can swing about the edge of the bridge, the threads become so embedded in the wall of the aperture that there is no danger whatever of the pin getting loose. The bridge also serves as an abutment for the pin to prevent it from 90 bending unduly under hard strain, for it will be seen that the hook *g³* on the pin is relatively close to the sounding board *a*, so that the end of the loop on the string is substantially below the top of the vertical side of the bridge. 95

Having thus explained the nature of the invention and described a way of constructing and using the same, although without attempting to set forth all of

the forms in which it may be made, or all of the modes of its use, I declare that what I claim is:—

1. A musical instrument having a bridge and a pin aperture, the mouth of which is substantially tangential to the bridge, and a hooked hitch pin located in said aperture to engage the bridge and having a threaded end adapted to be embedded in the wall of the aperture by a strain of the string upon the pin.
- 5 2. A stringed musical instrument having a bridge, and a hitch pin aperture whose mouth is substantially tan-

gential to the edge of the bridge, and whose axis is at an inclination to a perpendicular to the surface of the sounding board of the instrument, and a hitch pin having a hooked upper end and a threaded lower end.

In testimony whereof I have affixed my signature, in 15 presence of two witnesses.

JOSEPH R. GREEN.
